UNITED STATES PATENT OFFICE

97,255

DESIGN FOR A PNEUMATIC TIRE

Pierre Marcel Bourdon, Paris, France, assignor to
Michelin & Cie, Clermont-Ferrand, France, a
corporation of France

Application April 5, 1935, Serial No. 56,220

Term of patent 7 years

To all whom it may concern:

Be it known that I, Pierre Marcel Bourdon, a citizen of the French Republic and a resident of Paris, France, have invented a new, original, and ornamental Design for a Pneumatic Tire, of which the following is a specification, reference being had to the accompanying drawings, forming a part thereof.

Figure 1 is a fragmentary perspective view of a pneumatic tire, showing my new design.

Figure 2 is a fragmentary top plan view.
Figure 3 is a sectional view taken on the line 3—3 of Fig. 1.

I claim:
The ornamental design for a pneumatic tire as shown.

PIERRE MARCEL BOURDON.
